Attorney

UNITED STATES PATENT OFFICE.

HARRY G. BALTHASAR, OF ST. LOUIS, MISSOURI, ASSIGNOR TO COMBINATION AUTO LOCK COMPANY, OF ST. LOUIS, MISSOURI, A CORPORATION OF MISSOURI.

COMBINATION VALVE CONTROL.

1,253,770.

Specification of Letters Patent. Patented Jan. 15, 1918.

Application filed April 16, 1917. Serial No. 162,308.

To all whom it may concern:

Be it known that I, HARRY G. BALTHASAR, a citizen of the United States, residing at the city of St. Louis, in the State of Missouri, have invented certain new and useful Improvements in Combination Valve Controls, of which the following is a specification.

This invention applies the principle of a combination lock such as used in safes, vaults, and the like to prevent the operation of internal combustion engines, and provides means therefor. It is intended especially to prevent theft, misappropriation, or misuse 15 of motor vehicles and boats, aeroplanes, and the like.

In the accompanying drawings forming part of this specification and in which like numbers of reference denote like parts 20 wherever they occur,

Figure 1 is a sectional view showing this device in relation to the instrument-board of a motor-vehicle of a particular type requiring the tilting from the vertical or horizontal of parts of the said device;

Fig. 2 is a front elevation of the combination dial and button for revolving the same, taken on the line 2—2 in Fig. 1;

Fig. 3 is a view looking at Fig. 1 in the direction indicated by the line 3—3 in Fig. 1, with the protective casing removed;

Fig. 4 is a detail of the connection between the combination dial on the instrument-board and the operating shaft used in motor-35 vehicles not requiring the device to be tilted as shown in Fig. 1;

Fig. 5 is a detail of the index notches on the reverse side of the combination plate, taken on the line 5—5 in Figs. 1 and 4;

Fig. 6 is a detail of a permutation tumbler in plan view; and

Fig. 7 is a top plan view of the permutation device and means actuated thereby for governing the valve.

Upon the instrument-board 1 or at any other convenient or suitable place is mounted the combination dial 2, which is revoluble in both directions alternately by means of the knob 3, as is common in such constructions when used in safes and the like.

Referring first to Fig. 4, a plate 4 is placed between the combination dial and the instrument-board 1 with a flat spring 5 fas-

tened thereto at 6, the said spring having a pointer 7 adapted to engage notches 8 and 9 55 on the inner side of dial 2, which notches are shown in Fig. 5. Notch 9 is of especial depth. Thus, when dial 2 is rotated, the operator will notice the entrance of pointer 7 into each of the notches 8 and will thereby 60 be able to count the combination, but upon finishing the working of the combination will know by the feeling that the pointer 7 has seated in the deeper notch 9. The combination being thus indicated to the operator 65 by the feeling of pointer 7 riding over notches and the indication by the deeper notch 9 of its having been completely worked keeps the secret of the combination, as it is impossible for any one sitting along side the 70 operator to know what the combination is, as there is nothing visible on the exterior of the dial that will allow such observer to follow the working of the combination.

In the construction shown in Fig. 1, the 75 spring 10 is attached by screw 11 to arm 12 of plate 13, and the pointer 14 on spring 10 operates through an opening 15 in arm 12 to engage notches 8 and 9 (as described in connection with Fig. 4) on the reverse or in-side of dial 2.

The face of dial 2 may, if desired, bear spaced marks which may coincide with the notches upon the reverse side shown in Fig. 5 or misleadingly placed not opposite the 85 same, or the face of the said dial may be un-marked, inasmuch as the real working of the combination will not be by sight, but by the feeling of the pointer 7 (in Fig. 4) or pointer 14 (in Fig. 1) riding into and out of 90 the notches on the reverse side of dial 2.

Shaft 16 (the main part of which is not shown in the drawings) is a flexible shaft for operating the lock and valve, and shaft 17 is a non-flexible shaft for the same pur- 95 pose in a different type of machine.

Referring to Fig. 4, a bushing 18 having a collar 19 passes through the instrument-board 1 and is screw-threaded at 20 to receive the screw-threaded cap 21 having the 100 collar 22. The bushing 18 and the cap 21 are kept from rotation by the set-screw 23. A pintle 24 having a flattened end 25 to co-operate with the flattened end 26 of shaft 16 is rotatable by knob 3, which simultaneously 105 rotates dial 2, and collar 27 fastened to pintle

24 by a tapered pin 28 prevents retraction of knob 3 and pintle 24 through the bushing 18. Shaft 16 is held from retraction from cap 21 in any suitable manner, but is caused to rotate with pintle 24 by the coöperation of the flattened parts 25 and 26.

The butterfly valve 29 is normally open, with the parts in the positions shown in Figs. 1 and 3 and in full lines in Fig. 7. The 10 dotted lines in Fig. 7 show the position of certain parts when the butterfly valve 29 is closed.

Valve 29 is mounted on rod 30 and adapted to rotate therewith, the said rod passing 15 through a hole or bore 31 in plate 32, and one end of which rod seats in socket 33 in the said plate 32, the said rod thus extending across hole 34 in plate 32.

Plate 32 is located between the carbureter 20 35 and the intake manifold 36 in an internal combustion engine. The arrangement is the same if located at the exhaust manifold, as may be done. If located at the intake manifold the admission of gas from the carbureter is controlled by butterfly valve 29; if located at the exhaust manifold, the butterfly valve 29 controls the exhaust of the products of combustion.

The valve 29 is opened by the rotation of 30 rod 30, which is produced by pressure on the arm 37 by the lever 38, pivoted at 39 to the plate 40. The pressure of lever 38 on arm 37 is produced by the rotation of cam 41 by means of shaft 17 (or flexible shaft 35 16), the said cam 41 in its rotation (clockwise, as shown in the drawings) impinging upon lug 42 (or other suitable part) connected with lever 38. The lever 38 is rounded and beveled at its nose 43 in such manner as to slide easily on arm 37, which also is coöperatively shaped.

The cam 41 is fixed to rotate with shaft 17 (or shaft 16), while tumblers 44 and 45 are loosely mounted in relation thereto. Pins 46 on the said cam 41 and tumblers 44 and 45 are adapted to engage with each other in such manner that when cam 41 is rotated clockwise the pin 46 depending therefrom will engage with the pin 46 projecting upwardly from tumbler 44, and the pin 46 depending from tumbler 44 will engage with the pin 46 projecting upwardly from tumbler 45, with the result that the said tumblers will be rotated, thereby removing slot 47 50 from alinement with lug 42. A partial rotation of cam 41 suffices to force lug 42 out of slot 47, after which the pins 46 on cam 41 and tumbler 44 engage, whereupon the continued rotation of cam 41 causes the slot 47 55 in tumbler 44 to become out of alinement with lug 42, and thereafter rotation of cam 41 in either direction causes slot 47 in tumbler 45 to be out of alinement with lug 42. This movement consists in first forcing lug 60 65 42 out of slot 47 in both tumblers 44 and 45;

retaining the same by the periphery of cam 41 in such outwardly pressed position until slot 47 in tumbler 44 is moved out of alinement therewith, so that it will be held in its outwardly pressed position by the periphery 70 of tumbler 44 away from slot 47 therein; and then mixing up the combination by continued rotation or working it back and forth, which results in lug 42 being held out of slot 47 either by the high part of cam 41 or 75 by the periphery away from slot 47 of either tumbler 44 or 45 or both or of all three of the said members.

A suitable spring which in the drawings is shown as a coil spring 48 actuates both 80 the valve 29 and lever 38 bearing lug 42, so that lug 42 will instantly drop into slot 47 as soon as such slot in both tumblers 44 and 45 and the low part of cam 41 are in alinement. This will occur whenever the combination has been properly "worked" by some 85 one who knows it having made the requisite movements back and forth of knob 3 to cause engagement of pins 46 in such manner as to set the tumblers 44 and 45 and cam 41. It is requisite that means be provided to make 90 difficult tampering with the permutation tumblers. This provision need not attempt the qualities of a burglar-proof safe, but for the purposes necessary in connection with 95 locks used for the object herein contemplated, it is enough if the permutation tumblers be protected from ordinary interference, and in such manner that they cannot be tampered with without considerable work and 100 dismantling of the machine, requiring corresponding amount of work in replacement and installation of temporary expedients. As a rule, thefts of motor-vehicles or the like are entirely frustrated unless accomplished quickly.

For the purposes just referred to, a protective cap 49 is provided, which, for purposes of convenience, is attached by screw 50 to plate 40, but which for real security 110 is connected thereto and firmly held between the carbureter 35 and manifold 36 by bolts 51 that pass through holes 52 therein and holes 53 in a wing 54 of plate 40. In some makes of machines, the said wing 54 may lie 115 in the same plane as plate 40 and, in fact, be part of the same, but in a certain type of motor-vehicle the same must lie in a different plane, as shown in the drawings. The bolts 51 are the same bolts by which the carbureter 120 35 and manifold 36 are attached together, and removal of the same to obtain access to the permutation tumblers will necessarily take considerable time and seriously disarrange the mechanism and require either its 125 replacement or the installation of a temporary expedient between the carbureter and intake manifold.

The combination for any particular lock depends upon the positions of the pins 46 130

relative to each other on their respective members, and a plurality of holes (not shown in the drawings) may be provided in the cam 41 and in each of the tumblers 5 44 and 45 allowing for the change of position therein relative to each other of the pins 46, so that when the combination of any particular lock has been ascertained, as, for instance, by a chauffeur, it can be easily 10 changed by changing the pins 46.

Having thus described this invention, I hereby reserve the benefit of all changes in form, arrangement, order, or use of parts, as it is evident that many minor changes 15 may be made therein without departing from the spirit of this invention.

I claim:

1. A device of the character described comprising a plate adapted to be inserted in an 20 engine conduit and having an opening formed therethrough adapted to register with the bore of said conduit, an oscillatory valve disposed to close said opening, a rod by 25 which said valve is carried, said rod being mounted to turn in said plate, a crank extension upon the outer end of said rod, a swinging lever pivoted at one end, the crank extension of the rod lying in the path of movement of the opposite end of said lever, 30 means tending to turn the rod in one direction and permutation tumblers coacting with said swinging lever, at a point between its ends.

2. A device of the character described comprising a plate adapted to be inserted in the length of an engine conduit, and having an opening formed therethrough adapted to register with the bore of said conduit, a 35 valve adapted to close said opening, a rod 40 by which said valve is carried, said rod being journaled in said plate, an integral extension carried by said plate, and lying at an angle to the body portion of the plate, a lever pivoted to the face of said integral extension and swinging thereover, a crank extension upon the rod which lies in the path of movement of said lever, and a plurality 45 of permutation tumblers mounted upon said extension and coöperating with said lever, 50 as and for the purposes set forth.

3. A device of the character described comprising a plate adapted to be inserted in the length of an engine conduit, and having an opening formed therethrough, adapted 55 to register with the bore of said conduit, an oscillatory valve mounted in said opening, a rod by which said valve is carried, said rod being mounted to turn in said plate, a spring seated in a recess formed in said 60 plate, and surrounding said rod and acting to turn said rod in such direction as to move the valve to open position, a crank extension upon the outer end of said rod, an extension carried by said plate and lying at an 65 angle with respect to the body portion of

said plate, a lever mounted to swing over the face of said extension, the crank extension of the rod lying in the path of movement of said lever and a plurality of permutation tumblers mounted upon said extension, and coacting with said lever at a point intermediate its ends. 70

4. In a device of the character described, the combination of a stem, a cam and tumblers borne and rotatable thereby and each 75 having means for engaging the next adjacent member, a lever oscillatable by the said members, a spring-pressed arm adapted to be actuated by the said lever, and a butterfly valve mounted upon a shaft bearing the 80 said arm.

4. In a device of the character described, a valve so located as to control the passage of gas relative to the manifold of an internal-combustion engine, means for opening 85 or closing the same, the said means consisting of a plurality of tumblers, movable means actuatable by the said tumblers, means for actuating the said tumblers, one of the said tumblers being a cam adapted to actuate the said movable means, a casing inclosing the said opening and closing means, the said casing being composed of a plate having parts at substantially a right angle to each other, another plate having parts at 90 substantially a right angle to each other, and bolts for uniting the said two plates together.

6. In a device of the character described, a valve so located as to control the passage 100 of gas relative to the manifold of an internal-combustion engine, means for opening or closing the same, the said means consisting of a plurality of tumblers, movable means actuatable by the said tumblers, 105 each of the said tumblers having a stud thereon for engagement with another of the said tumblers, and one of the said tumblers being a cam adapted to actuate the said movable means, a protective casing for said tumblers comprising a pair of plates, one of them having a recess and both plates having a substantially right-angled extension 110 adapted for insertion between the manifold and an associated part, each of the said substantially right-angled parts having an opening therethrough and one of the said plates containing the said valve in the said opening, and bolts adapted for fastening 115 said substantially right-angled extensions together and to the manifold and associated part.

7. In a device of the character described, a valve so located as to control the passage 125 of gas relative to the manifold of an internal-combustion engine, means for opening or closing the same, the said means consisting of a plurality of tumblers, movable means actuatable by the said tumblers, and 130

means for actuating the said tumblers, the said tumblers being within a casing and the said last-mentioned means extending there-out and being operable by means external 5 of the said casing, the said valve being mounted on a rotatable spring-pressed member having an arm and the said movable

means being adapted slidingly to contact with and actuate the same when moving against said spring pressure and also to 10 yield under the said spring pressure.

In testimony whereof I hereunto affix my signature.

HARRY G. BALTHASAR.
